UNITED STATES PATENT OFFICE.

HELGA M. PETERSON, OF CHICAGO, ILLINOIS.

DEVICE FOR DECORATING CHINAWARE.

1,060,022.

Specification of Letters Patent.

Patented Apr. 29, 1913.

Application filed June 29, 1912. Serial No. 706,561.

To all whom it may concern:

Be it known that I, HELGA M. PETERSON, a citizen of the United States, residing at Chicago, in the county of Cook and State 5 of Illinois, have invented a certain new and useful Improvement in Devices for Decorating Chinaware, of which the following is a full, clear, concise, and exact description, reference being had to the accompanying 10 drawings, forming a part of this specification.

My invention relates to devices for decorating chinaware and has for its object the provision of a device which is readily adjustable for use in decorating china articles 15 of any size or conformation and one which may be economically manufactured.

While the pen which I prefer to use with my device is of a particular construction, 20 the ordinary ruling pens may be used with my device if desired.

My invention will be more clearly understood by referring to the accompanying drawings, in which—

25 Figure 1 is a side elevational view of my device; Fig. 2 is a top view thereof; Fig. 3 is a cross-sectional view taken on the line 3—3 of Fig. 1; Fig. 4 is an elevational view of the pen which I prefer to use with 30 my device; Fig. 5 is an elevational view of a modified form of the adjustable arm; and Fig. 6 is a cross-sectional view taken on the line 6—6 of Fig. 5.

Similar reference numerals refer to similar parts throughout the several views.

Referring now to Fig. 1, a rod or beam is indicated at 7. This rod has a split end indicated at 8 which is adapted to be spread and closed by means of a suitable thumb screw 9. The end of the rod 7 is conformed to receive a suitable ruling pen 10. The opening 11 which is provided to receive the pen 10 may be of the shape shown in Fig. 2, or it may have a rectangular shape as indicated in dotted lines. The rod 7 is provided with a suitable arm 12 disposed at right angles to the rod 7. This arm, which is adjustable on the rod 7, may be retained in any desired position by means of 45 a suitable thumb screw 13. The arm 12 which is preferably of square cross-section as shown in Fig. 3 may have one corner thereof provided with a plurality of notches 14. These notches are adapted to engage 50 the edge of a plate or vase or other article

with which the device is to be used. I prefer to have the arm of square cross-section in order that the portion of the arm which engages the china article may be as small as possible. In the drawings the arm 60 12 is shown mounted upon the beam with the notches on the side away from the marking tool. It is apparent, however, that the notches may be brought into use by reversing the arm relatively to the beam. The rod 65 7 is marked off into feet and inches to facilitate adjustment of the arm. The rod 7 may be provided with an auxiliary opening 11, if desired.

Referring now to Fig. 4, the preferred 70 form of ruling pen is shown. The front finger 15 of the ruling pen is preferably narrower than the rear finger 16 in order that it may be adjustable when the rear finger 16 is clamped within the split end of the rod 7. 75

In the modification shown in Fig. 5 the arm 12 may be provided with an adjustable notched block 17, if desired. This block is retained at the desired position by means of a suitable thumb-screw 18. When this arrangement is used, the position of the notch 80 may be adjusted to suit any requirements.

In using the device it is placed with one of the edges of the arm 12 resting against the edge of the article to be decorated and 85 then moved along the article, the pen being drawn over the surface of the article to mark thereon the desired line. Of course, the position of the arm relatively to the rod 7 is carefully adjusted before the device is 90 used.

While I have illustrated my device in the particular embodiments herein shown and described, I do not, however, limit myself to these exact constructions but desire to claim 95 any equivalents that may suggest themselves to those skilled in the art.

What I claim is:

1. In a device of the class described, a beam having linear graduations thereon, an arm 100 disposed at right angles to said beam, said beam having a split end, and a pen adjustably retained in said split end, said pen having one finger narrower than the other finger so that the narrow finger is adjustable relatively to the other finger when the said other finger is retained in the split end of the beam, said arm having a notch on the one side thereof, substantially as described. 105

2. In a device of the class described, a 110

beam, an arm disposed at right angles to said beam and adjustably mounted thereon, said beam being provided on one end thereof with means for carrying a suitable marking tool, said arm having one edge thereof provided with notches, said notches being adapted to engage the article with which the device is used when said arm is adjusted upon

10 said beam with the notches facing the marking tool.

In witness whereof, I hereunto subscribe my name this 26th day of June, A. D. 1912.

10 HELGA M. PETERSON.
